UNITED STATES PATENT OFFICE

2,331,068

COMBINATION UTENSIL

Joseph Di Pietro, Woodlawn, Md.

Application December 11, 1942, Serial No. 468,735

1 Claim. (Cl. 210—155)

My invention relates to improvements in combination utensils, the principal object in view being to provide a device of the character indicated for quickly and easily filling nursing bottles, and the like, and combining the advantages of both a funnel and a strainer, and which may be easily and thoroughly cleaned, used either as a combination utensil, or otherwise, as desired, is simple in construction and inexpensive to manufacture.

To the accomplishment of the above, and subordinate objects presently appearing, a preferred embodiment of my invention has been illustrated in the accompanying drawing, set forth in detail in the succeeding description, and defined in the claim appended hereto.

Figure 1 is a view in side elevation of my improved combination utensil, partly broken away,

Figure 2 is a view in plan, and

Figure 3 is a view in transverse section taken on the line 3—3 of Figure 2.

Referring to the drawing by numerals, according to my invention, a funnel 1 of the usual type and size suitable for filling nursing bottles is provided around the mouth thereof with an annular, extension neck 2 crimped to form internal threads 3 therein. Combined with the funnel 1 is a strainer unit comprising an annular frame 4 including a similarly shaped short skirt 5 crimped to provide external threads 6 thereon by means of which the neck 2 may be turned onto said skirt, as shown in Figure 3. The frame 4 is rolled around a double strand looped end 7 of a twisted wire handle 8 extending out from the frame 4 and equipped with the usual hand grip

9. A dished, mesh wire strainer 10 is suitably secured at its edges in the frame 4 to depend into the mouth of the funnel 1.

As will be readily apparent, the combined utensil described may be easily handled to insert the funnel in the mouths of nursing bottles and straining and filling may be quickly accomplished in the use of the same. Also the strainer unit and funnel 1 may be easily detached one from 10 the other for cleaning, or for use as separate units. Further, the device is simple in construction and adapted for manufacture for the low priced trade.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

In a utensil of the class described, a strainer comprising an annular frame including a threaded skirt, a dished strainer member fixed in said frame to depend out of said skirt, a funnel unit having a neck threaded onto said skirt, said frame having a rolled upper edge, and a twisted wire handle extending out of said edge and having a double strand looped end around which said edge is rolled.

JOSEPH DI PIETRO.
